US0D1082133S

(12) **United States Design Patent** (10) **Patent No.:** **US D1,082,133 S**
(45) **Date of Patent:** **** Jul. 1, 2025**

(54) **BATH BALL**

(71) Applicant: **Yunfeng Ji**, Yiwu (CN)

(72) Inventor: **Yunfeng Ji**, Yiwu (CN)

(**) Term: **15 Years**

(21) Appl. No.: **29/876,844**

(22) Filed: **May 30, 2023**

(30) **Foreign Application Priority Data**

May 8, 2023 (CN) 202330265297.4

(51) **LOC (15) Cl.** **28-02**

(52) **U.S. Cl.**

USPC **D28/7**

(58) **Field of Classification Search**

USPC D28/4, 7, 8.1, 9, 63

(57) **CLAIM**

The ornamental design for a bath ball, as shown and described.

DESCRIPTION

FIG. 1 is a front, left and top perspective view of a bath ball, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
